UNITED STATES PATENT OFFICE.

JOHN C. GRIFFIS, OF LOS ANGELES, CALIFORNIA, ASSIGNOR TO PACIFIC PIPE AND SUPPLY COMPANY, OF LOS ANGELES, CALIFORNIA, A CORPORATION OF CALIFORNIA.

DESIGN FOR A LAVATORY.

Application filed February 13, 1928. Serial No. 25,419. Term of patent 14 years.

To all whom it may concern:

Be it known that I, JOHN C. GRIFFIS, a citizen of the United States, residing at Los Angeles, in the county of Los Angeles and the State of California, have invented a new, original, and ornamental Design for Lavatory, of which the following is a specification, reference being had to the accompanying drawing, forming part thereof.

I claim—

The ornamental design for a lavatory as shown.

Signed at Los Angeles, Calif., this 8th day of February, 1928.

JOHN C. GRIFFIS.
